UNITED STATES PATENT OFFICE

2,605,831

ADJUSTABLE VENTILATOR SCREEN

David Jordan Rust and Jack H. Jensen, San Leandro, Calif., assignors to Ry-Lock Company, Ltd., San Leandro, Calif., a corporation of California

Original application March 25, 1949, Serial No. 83,388. Divided and this application May 7, 1951, Serial No. 224,956

2 Claims. (Cl. 160—375)

1

This invention is directed to a portable, initially separate, manually installed, ventilator screen adapted for use in an otherwise unscreened window to cover a partial opening thereof; the present application being a division of copending application, Serial No. 83,388, filed March 25, 1949, now Patent No. 2,564,011.

A major object of this invention is to provide a ventilator screen, for the purpose described, which is readily adjustable in length for engagement in window frames of different widths; the screen having upstanding, laterally shiftable, end slides to accomplish such adjustment, and there being novel means to prevent escape of the slides from the ends of the main screen structure, and said means serving at the same time to bar entry of flies or insects through the working space between said structure and slides.

An additional object of the invention is to provide a ventilator screen, as above, which embodies a novel guide arrangement between the main screen structure and the slides, so that the latter may be readily slid in or out as necessary to fit the device to a window frame.

Another important object of the invention is to provide a ventilator screen which, when in place in a window frame, permits of adequate ventilation through a partial opening of the window, yet allows the adjacent window sash to be opened or closed at will, and without manipulation or removal of said screen; the latter forming an effective fly and insect proof closure with the window frame and adjacent partially open window sash.

It is also an object of the invention to provide a ventilator screen which is of a simple design which is easy and economical to manufacture, but nevertheless is of durable, weather resistant metallic construction, so that the device can remain in place in a window frame from season to season.

Still another object of the invention is to provide a practical and reliable adjustable ventilator screen, and one which will be exceedingly effective for the purpose for which it is designed.

These objects are accomplished by means of such structure and relative arrangement of parts as will fully appear by a perusal of the following specification and claims.

In the drawings:

Fig. 1 is an inside elevation, foreshortened, of the adjustable ventilator screen.

Fig. 2 is an outside elevation, foreshortened, of said screen.

Fig. 3 is an enlarged cross section on line 3—3 55 of Fig. 1.

2

Fig. 4 is an enlarged fragmentary sectional plan view on line 4—4 of Fig. 1.

Referring now more particularly to the characters of reference on the drawings, the novel, 5 adjustable ventilator screen comprises a main screen structure or border frame, indicated generally at 1; such border frame including a horizontal top rail 2 and a horizontal bottom rail 3 spaced apart vertically a substantial distance.

10 The top rail 2 and bottom rail 3 are connected, at opposite ends, by flat end posts 4 disposed on the inside and affixed to said rails by flush connections, such as spot-welding 5; the upper ends of such posts 4 being out-turned over the upper edge of the top rail 2, as at 6, for the reason hereinafter described.

The main screen structure or border frame 1 comprised of the rails 2 and 3, and posts 4, is fitted with a screen section 7, which section is secured 20 in place as follows:

The top rail 2 is formed along its lower edge portion, and the bottom 3 is formed along its upper edge portion, with U-shaped channels, indicated at 8 and 9 respectively; the channel 8 opening 25 upwardly and the channel 9 opening downwardly.

The screen section 7 is folded along its upper and lower longitudinal edge portions, as at 10, and as so folded is clamped in the corresponding channels 8 and 9; the screen turning out of the channels and lying flush against the back or inner sides thereof. The channels 8 and 9 are offset forwardly, as shown, a distance such that the screen section 7 and the back or inner sides 30 of the rails 2 and 3 are in substantially the same vertical plane.

The main screen structure or border frame 1 is fitted, at opposite ends and on the outside, with upstanding, relatively wide slides 11; such slides being mainly flat but vertically ribbed, as at 12, 40 for strength.

At the top and bottom the slides 11 are each formed with inwardly offset transverse tongues 13 which ride the outer face of the rails 2 and 3 above and below the channels 8 and 9, respectively. The tongues 13 also engage in slidable relation in upper and lower longitudinal channels 14 and 15 formed by downturning and upturning the upper and lower edge portions of the top rail 2 and bottom rail 3, respectively.

50 As so mounted, the slides 11 are capable of substantial adjustment at corresponding ends and lengthwise of the main screen structure or border frame 1, whereby to project selective distances beyond opposite ends of said border frame.

In order to prevent the slides 11 from escaping the ends of the main screen structure or frame

1, the slides 11 are each formed on their laterally innermost edge with an inturned flange 16 which extends vertically between the channels 8 and 9; there being a minimum of space, as at 17, between the free edge of each flange 16 and the screen section 7.

Each of the end posts 4 is formed, at its laterally outermost edge, with an out-turned flange 18 which extends vertically full distance between the channels 8 and 9, covering the ends 10 of the latter.

With the arrangement of the cooperating in-turned flange 16 and out-turned flange 18, each slide 11 is limited in the extent to which it can be laterally outwardly projected; this for the reason that the flange 16 will abut the flange 18, preventing separation of the parts.

Also, by reason of the fact that each inturned flange 16 extends to a point close to the screen section 7, entry of flies or other insects through the space 17 is prevented.

At their laterally outermost edges the slides 11 are each formed with forwardly offset shoulders 19, which shoulders have locator lips 20 projecting laterally outwardly from their foremost edges.

Each of the slides 11 is fitted, centrally between the top and bottom thereof and adjacent the laterally outermost edge, with a friction locking device, indicated generally at 21, and which device is described in detail, with respect to its structure and function, in the aforesaid copending application.

When the above described ventilator screen is in use, it is engaged in a window frame, indicated generally at 22, in the manner shown in Figs. 3 and 4; the device resting at its lower edge on the sill 23, and the slides 11 being adjusted laterally outward until the shoulders 19 and locator lips 20 matchingly engage from the front with the adjacent parting beads 24 of said window frame. The locking devices 21 are then disposed in the adjacent sash channels 25, and are manipulated to engage against a forward stop 26 whereby to forcefully but releasably secure the ventilator screen in place.

When the ventilator screen is in use in a window frame, as above, the lower sash 27 is partially open, with its bottom cross bar 28 some distance above the sill 23, but not above the top rail 2 of the device. This permits of ventilation through the screen section 7, yet the device is fly and insect proof by reason of the fact that there is substantially complete closure with the sill 23, bottom cross bar 28 of the lower sash 27, and the parting beads 24. It should also be noted that the adjacent portion of the lower sash 27 runs in close face to face relation to the flat end posts 4; the upper ends or tips 6 of said end posts being out-turned, as shown, to assure against said ends or tips undesirably biting into the sash 27 as the latter is moved up or down.

The described adjustable ventilator screen is

formed, in the frame parts thereof, wholly of sheet metal—preferably of an aluminum alloy, thus being weather-proof and rust-resistant. Consequently, the ventilator screen may remain in place in a window frame for extended period of time without deterioration; the design being such that when in place the ventilator screen does not obstruct normal opening and closing of the sash 27.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. An adjustable ventilator screen comprising a sheet metal border frame having top and bottom rails and strap like end posts secured against the front face of the rails, said rails and posts defining a rectangular opening, the rails along their opening-forming edges being provided with longitudinal channels facing away from the opening and offset back from the posts, a rectangular screen panel behind and overlapping the posts with its top and bottom portions clamped in said channels, upstanding sheet metal slides at the opposite ends of the border frame back of the same, the top and bottom portions of said slides being bent to follow the upper and lower edges of the upper and lower channels respectively and to then bear against the back of the rails above and below the top and bottom channels to adjacent the top and bottom edges of said top and bottom rails, and guide channels formed along such edges of the rails in which the corresponding edge portions of the slides engage.

2. A screen as in claim 1, in which the laterally inner edges of the slides, between the upper and lower channels are deflected to adjacent the screen, while the laterally outer edges of the posts, between the upper and lower channels are formed with rearwardly projecting flanges extending to adjacent the slides.
